UNITED STATES PATENT OFFICE.

SAMUEL S. MORTON, OF PHILADELPHIA, PENNSYLVANIA.

ENDLESS-TREAD CHAIN.

1,427,542.

Specification of Letters Patent. Patented Aug. 29, 1922.

Application filed August 1, 1921. Serial No. 489,056.

To all whom it may concern:

Be it known that I, SAMUEL S. MORTON, a citizen of the United States, residing at Philadelphia, in the county of Philadelphia and State of Pennsylvania, have invented 5 certain new and useful Improvements in Endless-Tread Chains; and I do declare the following to be a full, clear, and exact description of the invention, such as will enable others skilled in the art to which it 10 pertains to make and use the same.

My invention relates to improvements in endless tread chains such as those used on tractors, tanks and other heavy machines 15 requiring that their weight be equally distributed over quite an extensive area. Chains of this type are usually trained around front and rear sprockets but when a noticeable amount of wear has taken place 20 on the pivots which connect the several links, said links have a tendency to climb the teeth of the sprocket wheels, often producing very injurious results.

The object of my invention however is to 25 provide a novel form of tread chain embodying means for adjusting the spaced relation of the several links regardless of the amount of wear which may have taken place, so that the chains will at all times properly 30 mesh with the teeth of the sprocket wheels.

With the foregoing in view, the invention resides in the novel construction and association of parts hereinafter described and claimed, the descriptive matter being sup- 35 plemented by the accompanying drawings.

Figure 1 is a fragmentary side elevation of a tractor equipped with the chain.

Figure 2 is a side elevation of several links.

Figure 3 is a plan view.

Figure 4 is a longitudinal section on line 4-4 of Fig. 3.

Figure 5 is a vertical transverse section on line 5-5 of Fig. 2.

In the drawings above briefly described, I have shown a portion of a tread chain 1 constructed in accordance with the present invention and have illustrated the front sprocket 2 of a tractor, over which the chain 45 is trained, the lower reach of said chain being received between spaced plates 3 which however form no part of the present invention.

The tread chain 1 is constructed of a plu- 55 rality of pivotally connected links, each of said links comprising a tread plate 5 having

on its inner side a pair of longitudinal flanges 6 whose ends are so offset that the flanges of the several links may properly overlap. Each flange 6 is provided in one 60 end with an eye 7, at its other end with a longitudinal notch or slot 8, between its ends with a relatively large recess 9, and is additionally formed with an opening 10 leading from this recess to the slot 8. A 65 pivot pin 11 passes through the eyes 7 of each link and the projecting ends of this pin are received in the slots 8 of the next adjacent link, being secured to the latter by adjusting bolts or screws 12 which pass 70 through the openings 10 and are here shown threaded through the pins 11. The heads of the bolts 12 are located in the recesses 9 and are preferably provided with openings through which cotter pins 13 pass, 75 said pins being adapted to strike the intermediate portions of the flanges 6 and thereby lock the bolts against rotation after adjustment.

In the present showing, the pivot pins 80 11 are received between the teeth of the sprocket wheel 2 and thus form the driving connections between the chain 1 and said sprocket wheel and whenever any wear takes place which causes said pins to have a tendency 85 to climb the teeth of the sprocket, the pins may be relatively adjusted by means of the bolts 12 so that they will be spaced to such an extent as to cause them to accurately mesh with the sprocket teeth, 90 thereby obviating a great deal of difficulty which would otherwise be encountered.

Since excellent results may be obtained from the details disclosed, they are by preference followed, but within the scope of the 95 invention as claimed, numerous minor changes may be made.

I claim:

1. An endless tread chain comprising a plurality of overlapping links each having 100 a longitudinal slot in one end, a pivot pin carried by the other end of each of said links and slidably received in the slot of the next adjacent link, and screw-threaded adjusting devices acting on each pivot pin and reacting on the next link engaged by said pivot pin, for adjusting the pin in its receiving slot.

2. An endless tread chain comprising a plurality of overlapping links each having 110 a longitudinal slot in one end, a recess between its ends, and an opening extending

from said recess to said slot, a pivot pin carried by the other end of each of said links and slidably received in the slot of the next adjacent link, and bolts connected 5 with said pins and extending through said openings for adjusting said pins in said slots and consequently adjusting the spaced relation of said links.

3. In an endless tread chain, a plurality 10 of links each comprising a tread plate having a pair of longitudinal flanges on its inner side, each flange having an eye in one

end, a longitudinal slot in its other end, a recess between its ends and an opening leading from said slot to said recess; a pivot pin passing through the eyes of each of said links and slidably received in the slots of the next adjacent link, and bolts connected with said pins and received in said openings of the links for relatively adjusting the latter. 15 20

In testimony whereof I have hereunto set my hand.

SAMUEL S. MORTON.
